CLAIM

The ornamental design for a belt-mounted utility hitch,
as shown and described.

DESCRIPTION

FIG. 1 is a perspective view of the belt-mounted utility
hitch, showing my new design;

FIG. 2 is a front elevation of the belt-mounted utility
hitch;

FIG. 3 is a rear elevation thereof;

FIG. 4 is a left side elevational view, the right side being
a mirror image thereof;

FIG. 5 is a top elevation thereof; and,

FIG. 6 is a bottom elevation of the belt-mounted utility
hitch illustrated in FIGS. 1-5.

FIG. 6
